Howard C. Thompson
ATTORNEY

UNITED STATES PATENT OFFICE.

DAVIS MARINSKY, OF BRONX, NEW YORK.

FASTENING DEVICE.

Application filed March 23, 1925. Serial No. 17,583.

To all whom it may concern:

Be it known that I, DAVIS MARINSKY, a citizen of the United States, and residing at Bronx, in the county of Bronx and State 5 of New York, have invented certain new and useful Improvements in Fastening Devices, of which the following is a specification, such as will enable those skilled in the art to which it appertains to make and 10 use the same.

This invention relates to fastening devices and particularly to devices of this class adapted to couple and uncouple two or more parts to retain said parts in locked 15 position against accidental displacement when said parts are coupled together, and the object of the invention is to provide a device of the class specified with means extending through the interlocking portions 20 of the separate parts of the device for reinforcing said parts and also for providing means in connection with which the attaching strips of devices of the class specified operate to prevent the breaking of the same 25 when the device is in use; a further object being to provide a strand of flexible material for the purpose specified which will increase the strength of the attaching device and yet not interfere with the flexibility thereof; and with these and other objects in view the invention consists in a device of the class and for the purpose specified 30 which is simple in construction, efficient in use and which is constructed as hereinafter 35 described and claimed.

The invention shown and described herein is an improvement on that shown and described in applications filed by me January 21, 1925, Serial Nos. 3,738 and 3,739 40 and another application filed by me January 22, 1925, Serial No. 3,923, and is fully disclosed in the following specification, of which the accompanying drawing forms a part, in which the separate parts of my improvement are designated by suitable reference characters in each of the views, and in which:—

Fig. 1 is a plan view of a part of a fastening device made according to my invention 50 and indicating the same mounted in connection with a portion of two parts to be coupled together;

Fig. 2 is a partial sectional view on the line 2—2 of Fig. 1 and on an enlarged scale;

Fig. 3 is a partial section on the line 3—3 of Fig. 2;

Fig. 4 is a sectional detail view showing a part of the construction shown in Fig. 2; and,

Fig. 5 is a view similar to Fig. 4 but showing a modification.

In Fig. 1 of the drawing I have indicated at 10 and 11 two parts of a garment or apparel of any kind or class, or of any other article or apparatus to be coupled together 65 by a fastening device 12 which may be in conventional form employing interengaging and interlocking link members 13 and 14 of loop or ring formation, said devices being mounted on flexible strands 13^a and 14^a, and 70 the link members are adapted to be moved into and out of engagement by a slideable coupling block 15, and the link members 13 and 14 which are divided into sections, as is apparent, are secured to the parts 10 75 and 11 respectively by means of attaching strips 16 and 17.

The foregoing construction may be similar to that shown and described in detail in the applications above referred to, or in 80 any form of devices employing loop or ring-shaped link members, the distinctive feature of my present invention resides in the provision of flexible strands 18 and 19 which are adapted to extend through the 85 loops or rings of the link members 13 and 14, as clearly seen in Figs. 2, 3 and 4 of the drawing, and around which the folded and apertured portions 16^a and 17^a of the strip 16 and 17 are adapted to pass. 90

In carrying my invention into effect after the link members 13 and 14 have been formed and mounted upon the strands 13^a and 14^a, the strands 18 and 19 are passed through the loops or rings of said link members in the manner seen in Figs. 3 and 4 of the drawing, after which the attaching strips 16 and 17 are passed over the loops of the separate link members, said loops passing through the central apertured portion 16^a and 17^a thereof and are folded around the strands 18 and 19 as clearly seen 100 in Fig. 2 of the drawing, after which the end portions of the strips 16 and 17 may be stitched together and to the parts 10 and 11 105 in connection with which they are to be mounted as will be apparent. The strands 18 and 19 may be composed of any suitable flexible material, for example heavy cord or twine, light cable or flexible wire, and 110 may be of any cross sectional form, round or circular form being preferred.

By employing the strands 18 and 19 the link members 13 and 14 are additionally reinforced in their coupling one with the other in the separate series, and further the attaching strips 16 and 17 are reinforced at the apertured portions 16^a and 17^a thereof and the breaking or raveling of said apertured portions of said strip is obviated. The strands 18 and 19 also operate to limit the inward movement of the separate link members 13 and 14 and retain the separate sections formed by said link members in proper spaced relation at all times. It will also be noted, in the construction shown, that the loops of the link members 13 are offset in one direction at their outer end portions while the loops of the link members 14 are straight, and I am not necessarily limited to this or any other specific shape or form of the link members, or the method of their construction and mounting.

In Fig. 5 of the drawing I have shown a slight modification in which the link members 13 and 14, the link member 13 only being shown for illustration, are fashioned to form substantially circular recesses 20 in the loop portions of the link members to receive the strands 18 and 19, or the strand 18 as shown, this construction will reinforce the loops of the separate link members and will also operate to retain the strands 18 and 19 in proper position at all times. It will be understood that the attaching strips 16 and 17 are also employed in connection with the construction shown in Fig. 5 of the drawing, and that both the link members 13 and 14 will be of similar construction.

It will be understood that while I have shown and described one method of carrying my invention into effect, that I am not necessarily limited in this respect, and various changes in and modifications of the construction herein shown and described may be made, within the scope of the appended claims, without departing from the spirit of my invention or sacrificing its advantages.

Having fully described my invention, what I claim as new and desire to secure by Letters Patent, is:—

50. 1. A device of the class described comprising a plurality of link members having loop portions arranged in alinement, a flexible mounting strand on which said link members are mounted in abutting relation, a supplemental strand extending through the loop portions of said link members for reinforcing the same, and attaching means positioned between the loop portions of said link members and engaging the second named strand.

60. 2. A device of the class described comprising a plurality of link members having loop portions arranged in alinement, a flexible mounting strand on which said link members are mounted, a supplemental strand

extending through the loop portions of said link members for reinforcing the same, and an attaching strip through which the loop portions of said link members pass, said strip passing around the second-named strand. 70

3. A device of the class described comprising a plurality of loop members arranged in spaced relation, means to which said loop members are secured for retaining said loop members in spaced relation, a flexible strand extending through said loop members and adapted to reinforce the same and an attaching strip passing around said strand and by means of which the device is 80 secured to a suitable support. 75

4. In a fastening device of the class described employing a plurality of spaced loop members arranged in common axial alinement, a strand of flexible material independent of said loop members and extending therethrough, means independent of said strand for joining the separate loop members and to which said loop members are secured, and means engaging said strand for 90 securing the device to a support. 85

5. In a fastening device of the class described employing a plurality of spaced loop members arranged in common axial alinement, a strand of flexible material independent of said loop members and extending therethrough, means independent of said strand for joining the separate loop members, and to which said loop members are secured and an attaching strip through 95 which said loop members are adapted to pass, said strip being folded around said strand. 100

6. A device of the class described comprising a flexible strand, a plurality of link members secured to said strand and projecting therefrom in spaced arrangement and in common alinement, the projecting portions of said link members being of closed loop formation, a flexible strand passed through the loops of said link members and an attaching strip through which the projecting loops of the link members is passed and adapted to extend around said flexible strand. 110

7. A device of the class described comprising a flexible strand, a plurality of link members secured to said strand and projecting therefrom in spaced arrangement and in common alinement, the projecting portions of said link members being of loop formation, and a flexible strand passed through the loops of said link members and located adjacent said first-named strand and in parallelism therewith, and means for attaching the device to a suitable support, said means engaging the second named strand. 115 120

8. A device of the class described comprising a flexible strand, a plurality of link members secured to said strand and project- 125

ing therefrom in spaced arrangement and in common alinement, the projecting portions of said link members being of loop formation, a flexible strand passed through the 5 loops of said link members and located adjacent said first-named strand, and an attaching strip through which the loop members of said links are adapted to pass, said strip being foldable around the second-named 10 strand.

9. A fastening device of the class described comprising two interengaging and interlocking sections, each of said sections being composed of a plurality of link members 15 having projecting loop portions adapted to interlock one with the other of the separate sections in coupling said sections together, strands of flexible material passed through the loop portions of the separate 20 sections, attaching strips on each of said sections for mounting the same in connection with suitable supports, and said strips being foldable around said strands.

10. A device of the class described comprising two flexible strands arranged in parallel relation, a plurality of link members 25 mounted on said strands, said link members being secured to one of said strands and attaching means engaging the other of said 30 strands.

11. A device of the class described com-

prising a plurality of link members, each of said link members consisting of two closed loop portions, flexible strands extending through the separate loop portions of said link members and in substantially parallel relation, one of the loop portions of said link members being compressed onto the strand extending therethrough for securing said link members to said strands, and an attaching strip engaging that part of the other strand position between the loops of said link members. 35 40

12. A device of the class described comprising a plurality of link members, each of said link members consisting of two closed loop portions, flexible strands extending through the separate loop portions of said link members and in substantially parallel relation, one of the loop portions of said link members being compressed onto the strand extending therethrough for securing said link members to said strand, and an attaching strip engaging that part of the other strand positioned between the loops of said link members and the other loop portion of said link members being fashioned to partially encircle the other strand. 50 55

In testimony that I claim the foregoing as my invention I have signed my name this 20th day of March 1925. 60

DAVIS MARINSKY.
